UNITED STATES PATENT OFFICE

122,517

DESIGN FOR A COMBINED SIGNAL SWITCH AND SUPPORT THEREFOR

John Ralph Haines, Medford, N. J.

Application July 20, 1938, Serial No. 78,600

Term of patent 7 years

To all whom it may concern:

Be it known that John Ralph Haines, a citizen of the United States, residing at Medford, county of Burlington and the State of New Jersey, has invented a new, original, and ornamental Design for a Control Signal Switch and Support Therefor, of which the following is a specification, reference being had to the accompanying drawing, forming a part thereof.

Figure 1 is a side perspective view of the com-

bined signal switch and support therefor, showing the new design, and

Figure 2 is a fragmentary side elevational view showing how the switch body joins the upper portion of the support.

I claim:

The ornamental design for a combined signal switch and support therefor, as shown.

JOHN RALPH HAINES.
